INVENTOR:
MARY MURRY.
BY *Arthur C. Eckert*
ATTORNEY.

UNITED STATES PATENT OFFICE.

MARY MURRY, OF ST. LOUIS, MISSOURI.

GAME.

Original application filed September 19, 1927. Serial No. 220,365. Divided and this application filed April 2, 1928. Serial No. 266,516.

This is a divisional application divided out of applicant's patent application for games filed September 19, 1927, Serial No. 220,365. The object of my invention is to devise a game, particularly of an educational character; one that may be readily and advantageously played in a school room, one that will teach, recall, or impress such information as the crops of various States and countries, as the similarity of certain crops in different States and the dis-similarity in others, on the mind, as a similarity of rivers, lakes, mountains, etc., that are found or pass through different States or countries. The game is illustrated in the drawing as used principally in teaching minors geography. A further object is to make an educational game that may be easily and cheaply made of few and simple parts that lend themselves readily to multiple production.

With these and other objects in view, my invention has relation to certain novel features of construction and arrangement of parts as will be hereinafter more fully described, pointed out in the claim and illustrated in the drawing, in which,

Fig. 1 is a front elevation of a type of card used in the game.

Fig. 2 is a second type of card that is used in the game.

Fig. 3 is a card that may be used when my game is played a certain way. The cards are made of cardboard, aluminum, or other light and rigid material. The cards are divided longitudinally into three equal spaces, each card having the outline of a State in the central division and having a crop of the State printed in each of the lateral subdivisions, for example in Fig. 1 a card is shown having an outline of the State of Illinois in the central division and corn in the left hand lateral sub-division and wheat in the right hand sub-division; in Fig. 2 a card is shown having the outline of the State of Iowa in the central sub-division and corn in the left lateral sub-division and oats in the right hand lateral sub-division. The picture of the crop as well as its name is illustrated. The name of the State is printed in its outline.

Figure 3 designates a structure used in a modified form of play. The student having Michigan does not come forward immediately, because he is not sufficiently advised as to all the leading crops of that State. It

is to increase this knowledge that the game is played.

It will be observed that in the illustration indicated in Fig. 1 and Fig. 2, corn appears on both because it is one of the principal crops of both Illinois and Iowa. Instead of crops, minerals or other products may be taken. In playing the game, cards such as illustrated in Figs. 1 and 2 are distributed among the students of a class, one to each student. One student is selected at random to place his card on the chalk rail or other point of vantage. The remainder of the students then examine the cards and if a product is illustrated on their card corresponding to one of the products illustrated on the card on the rail, he comes forward and places his card on the rail immediately adjacent the card on the rail so that the corresponding crops illustrated will be juxtaposed, that is, if the card illustrated in Fig. 1 were placed on the rail by the first student, the student holding the card illustrated in Fig. 2 would place his card on the rail so that the corn illustrations would be positioned side by side. In the illustration supposed, it will be seen that it will be necessary to place the card illustrated in Fig. 2 upside down. This may be avoided by placing the like products on opposite sides of the cards, that is, in Fig. 2 corn may be placed in the space occupied by the oats illustration and the oats may be placed in the space occupied by the corn illustration. The second pupil as well as the first and the remaining students in the class will now be impressed with the fact that corn is the leading product in both Iowa and Illinois. The effect of performing these operations greatly impresses these facts on the student. He learns more rapidly than if he simply read the facts from a book and experience shows that the information is retained a great deal longer. The process continues until no more matching of products seems possible. The matching is done from both sides of the initial card and from both ends of the line of cards. If there are cards remaining in the hands of students, the operation is repeated on another rail or point of vantage, or on the same rail by leaving a space between each end of the original line of cards.

In order to show, for example, six products of Wisconsin, make three cards like those illustrated in Fig. 1, having the configuration

of the State of Wisconsin in the central division. On the first card place rye on one side of the State map and barley on the other; on the second, oats on one side and potatoes on the other; and on the third timber and iron. Then make three additional cards after the manner previously indicated.

The cards may be made with different illustrative arrangements, for example, the cards 10 may be laid vertically and again divided into three equal sub-divisions, with the State configuration in the central division and a product designation in the upper and lower spaces.

Another arrangement may be made with 15 triangular cards divided into a similar central triangle and surrounded by three triangles, each having one edge of the card for one of its sides. In this illustration the State configuration is placed in the central triangle and product designations and configurations 20 are placed in the surrounding triangles.

Another design of card may be a rectangular card divided into three vertical central divisions and two lateral end divisions. The 25 name of the State and its configuration is placed in the middle central division and names of the products of the State together with their configurations are placed in the remaining sub-divisions.

30 Another arrangement may be a card having five squares formed thereon, which squares form a cross, the name of the State and its configuration being in the central square and the names of the products and 35 their configurations being in the remaining squares.

In the triangle card and in the cards on which four products are shown, the names of the products may be enlarged as in the forms 40 previously designated. The idea may be similarly carried out with any polygonal shaped card.

As a modification of the play of the game, each student may be given an individual set 45 of cards for use at his desk. In this case he does the matching on his desk by placing the first card at random and then matching the cards as was previously described.

The idea may be similarly carried out by 50 making a card, for example, as shown in Fig. 1 but have the configuration of one product positioned in the central sub-division and the

names of States in which this is the principal product indicated by name and configuration in the lateral sub-divisions. In play, these 55 cards match the States rather than the product of the States.

As a further modification, Fig. 3 designates a large cardboard which is placed before the class. The card is slotted as shown 60 by the double lines and the name of a product is placed adjacent each slit. In the center of the card are placed the words "What State?". In playing the game the student uses the cards illustrated in Figs. 1 and 2 in connection with the card shown in Fig. 3. The pictures on the cards shown in Figs. 1 and 2 are made to match the names found on the card board shown in Fig. 3. The large cardboard 65 is exhibited so that it is visible to all students who are to play the game and each student is provided with cards of the type shown in Fig. 1 and Fig. 2. One student upon the examination of his card sees the word "Rye" on the large card and on his own card he sees a map 70 of North Dakota with a picture of rye on one side of the map. This student then comes forward and slips his card into the slit in the cardboard illustrated in Fig. 3 that has the legend "Rye" nearest it. Other students 75 having North Dakota cards come forward to help the first student, but soon decide that North Dakota does not lead in some of the products indicated on the cardboard shown in Fig. 3. The class continues to experiment 80 in this way until the correct State is found, that is to say, a State that has as leading products those indicated in the cardboard shown 85 in Fig. 3. When the proper set of cards has been finally fitted into the cardboard illustrated in Fig. 3, the student will discover 90 that Michigan is the name of the required State.

This same theory may be carried out for 95 cities and their manufactured products.

What I claim and mean to secure by Letters Patent is:

A game card having the legend "What State?" indicated thereon and products of the State indicated thereon, the card being slotted adjacent each product designation to admit 100 the insertion of another card.

In testimony whereof I affix my signature.
MARY MURRY.
